INK DELIVERY REGULATING DEVICE FOR
PRINTING PRESS INK FOUNTAINSEmery W. Worthington, Chicago, Ill., assignee to
Goss Printing Press Company, Chicago, Ill., a
corporation of Illinois

Application September 16, 1944, Serial No. 554,417

13 Claims. (Cl. 101—365)

1

The present invention pertains primarily to adjustment mechanisms for printing press ink fountains although in some of its aspects it may find a broader field of utility not only for adjustment of other devices in printing presses but also devices of other machines and the like.

One object of the present invention is to make possible the adjustment, either individually, or simultaneously in selected groupings, of a press-wide series of columnar ink delivery regulating devices in an ink fountain for a printing press, all through the use of a unified control station embodying a single manual operating knob or the like and set of selectors which may, if desired, be located some distance from the fountain, as for example in a convenient waist-high position at one side of the press, and which requires but a single operating shaft running back to the fountain, as contrasted with the multiple shaft arrangements with one shaft for each adjusting device in the fountain heretofore commonly used and shown, for example, in S. G. Goss Patent No. 869,237, issued October 29, 1907.

Another object is to provide an arrangement of the character indicated above which affords optionally available individual adjustment of the regulating devices at the fountain.

Another object is to provide such an arrangement in which the changes in adjustment effected at the control station are signaled to the operator not only visually but preferably also through the sense of touch. In other words, the operator can both see and feel the changes he is making.

Still another object is to provide an adjusting mechanism for printing press ink fountains in which provision is made for selective coupling of a desired one or more of a press-wide series of columnar adjusting screws or the like to a single drive shaft through the use of a coupling arrangement which obviates the necessity of moving either the driving or driven elements when coupling them, in contrast with an ordinary clutch, and which is operated by simple, low-cost and low-power electromagnets of the form commonly employed in relays.

Further objects and advantages of the invention will become apparent as the following description proceeds, taken in connection with the accompanying drawings, in which:

Figure 1 is a perspective view of a rotary printing press unit equipped with adjusting apparatus embodying the present invention and arranged to control the delivery of ink from the ink fountain of such unit.

2

Fig. 2 is an elevation, taken from the control panel side, of the unit of Fig. 1.

Fig. 3 is a more or less diagrammatic view, showing on exaggerated scale the spacing of the fountain roller with reference to its coating film regulating blade and pick-up roller.

Fig. 4 is an enlarged face view of one of the control panels of the unit of Figs. 1 and 2.

Fig. 5 is a sectional view taken substantially along the line 5—5 in Fig. 4 and also showing a portion of the shafting connected to the operating knob associated with the panel.

Fig. 6 is a simplified wiring diagram for a portion of the switches on the control panel.

Fig. 7 is a fragmentary plan view of the adjusting mechanism applied to the ink fountains of the printing unit of Figs. 1 and 2.

Fig. 8 is an enlarged fragmentary sectional view taken substantially along the line 8—8 in Fig. 2 through the housing for the adjusting mechanism located above one of the ink fountains, and one of the electromagnets being removed to expose the bracket which stands behind it.

Fig. 9 is a transverse sectional view taken substantially along the line 9—9 in Fig. 8.

Fig. 10 is a fragmentary perspective view showing one of the adjusting screws, its associated actuating gearing and control electromagnet.

Fig. 11 is a fragmentary detail view of the adjustment mechanism drive shaft and gearing carried thereby, with the latter partially sectioned along the line 11—11 in Fig. 9.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the exemplary embodiment of the invention herein illustrated, it will be seen upon reference to Figs. 1 and 2 that the invention has been illustrated as incorporated in apparatus installed on a rotary printing press unit 10 of familiar general layout. Such press unit embodies first and second printing or plate cylinders 11 with coating impression rollers 12 and between which a web W may be led in a usual manner as indicated. Ink is supplied to the plate cylinders by inking mechanisms including rollers 14 and to which ink is in turn delivered

by respective ink supply mechanisms designated generally as 15.

Various forms of ink supply mechanisms may be used in press units of the style indicated, although in some aspects the present invention is particularly concerned with the illustrated type employing a fountain roll carrying an ink film of regulated thickness picked up by a closely adjacent non-contacting pick-up roll. Each supply mechanism 15 herein shown includes an ink fountain 16 suitably mounted upon the press framework in position to extend transversely across the lower portion of the appropriate end of the press unit. In each fountain 16 is a rotatively driven fountain roller 17 partially submerged in a bath of ink whose level is indicated at 18. The ink is taken from the fountain roller 17 by a pick-up roller 19 frictionally driven from the lowermost one of the series of inking rollers 14 with which the pick-up roller runs in direct contact. The fountain and pick-up rollers 17, 19 are spaced apart by a small clearance of the order of a few thousandths of an inch. By precision regulation of the thickness of the ink film on the fountain roller the rate of delivery of ink to the pick-up roller and thence to the inking mechanism may be accurately determined. Moreover, by diminishing the thickness of the ink film on the fountain roller to an amount less than the clearance between such roller and the pick-up roller, the delivery of ink to the latter may be stopped altogether. The clearance between the fountain and pick-up rollers is indicated by c in Fig. 3, while f indicates the thickness of ink film on the fountain roller.

To regulate the thickness of the ink film on the fountain rollers 17, one or more resilient, laterally flexible blades 20 (Figs. 3, 8 and 9) are employed. Such blades are located with their free edge portions extending longitudinally of the associated fountain rollers and overlying the peripheral portions of the latter which carry the ink film from the ink bath to the pick-up rollers. Any desired number of such blades may be used for each fountain roller, four of them arranged end-to-end being desirable in a newspaper press of the general style illustrated, since the latter is commonly adapted to receive a paper web W of four-page width, and each of the four blades may thus be of one-page width. In the present instance the blades 20 are shown as clamped by a longitudinally extending retaining strip 21 fixed by screws 22 to the underside of a channel-shaped housing 23. The latter is in turn bolted at its ends to the respective ends of the fountain 16 in position to extend longitudinally above the latter. The otherwise open outer portion of the top of the fountain is closed by a suitable cover 24 hinged on the housing at 25 (Fig. 9).

Adjusting screws 26 (Figs. 8, 9 and 10) serve to vary the displacement of the edges of the blades 20 with reference to the fountain rollers 17 to alter correspondingly the thickness of the ink films on the latter. Desirably one such screw is provided for each columnar width along the length of the blades or, in other words, a press-wide series of thirty-two screws is used in the present instance to accommodate a four-page width with eight columns per page. The screws 26 are generally normal to the side faces of the blades 20 opposite the fountain rollers 17, being threaded in appropriately spaced tapped holes 27 in the bottom of the housing 23 with their rounded noses 26a bearing against the underlying faces of the blades so that by threading the

screws in or out the blades may be flexed accordingly. The screws are disposed in a series transversely of the press unit, being arranged in a single line for each fountain in the present instance (see Fig. 1). Each of the blades 20 is sufficiently flexible that a portion thereof of substantially single column width on the press may be flexed laterally by the corresponding adjusting screw throughout the range of movement required without materially affecting the laterally adjacent portions of the blade operated upon by the adjacent adjusting screws in the series. It will thus be seen that by turning the individual adjusting screws 26 the amount of ink delivered to corresponding columnar portions of the press may be varied with nicety and precision.

The present invention makes possible highly accurate and fully selective rotational adjustment of any desired number of the screws 26 by a single driver which is operated and selectively coupled to the screws by controls which may be located at a point more or less remote from the fountain. Although such driver may be revolved either by power or by hand, manual operation is preferred since it makes it possible for the operator to "feel" the successive increments of adjustment imparted as will hereinafter appear in detail. Similarly, it is preferable to provide a separate control station for each half of the press unit in order that the operator in using the same may conveniently observe the hereinafter described visual indicators which show the prevailing positional adjustment for each of the several screws 26.

In the instant embodiment two control stations or sets of controls, designated generally as 28 (Fig. 1) are provided for respective ones of the two sets of adjusting screws 26 and are located at the same side of the press unit. Since the two control stations are identical, a description of one will suffice for both. As here shown (see Figs. 1, 4 and 5) each such station 28 includes a single manual operating knob or handle 29 and a group of selector switches 30, one of the latter for each adjusting screw. In brief, the arrangement is such that the operator has only to snap on the desired one or ones of the selector switches to connect the operating knob 29 drivingly to the corresponding screws for rotational adjustment of the latter in accordance with turning of the knob. The operator is thereby relieved of the necessity of stooping down to floor level for the tedious and exacting adjustment of the numerous individual adjusting screws.

Referring to Figs. 4 and 5, it will be seen that the righthand control station 28 there shown comprises a panel 31 fixed to the press frame in slightly inclined position and carrying the selector switches 30. The latter are enclosed at the rear side of the panel by a suitable housing 32. The selector switches may be ordinary double-pole, two-position tumbler switches of the snap-acting type having operating handles 30a. The panel 31 bears suitable identifying numbers beneath each switch handle correlating the same with the corresponding adjusting screws, and also bears appropriate indicia of the "on" and "off" positions for the switches.

The operating knob 29 is pinned to a stub shaft 33 journaled in a bracket 34 and projecting through a suitable aperture beneath the group of selector switches 30 so as to be readily available for manipulation in conjunction with these switches. A single drive shaft 35 (Fig. 8) is used for imparting motion derived from the

operating knob 28 to selected ones of the adjusting screws 26. In the present instance such shaft projects longitudinally through the housing 23, being journaled in suitable bearings (not shown) at opposite ends of the latter. An axially aligned extension shaft 36 is coupled to the forward end of the drive shaft (see Fig. 1), being connected at its forward end by bevel gears 37 (see also Fig. 5) to an upright shaft 38, and the latter is in turn connected by bevel gears 39 with the stub shaft 53 carrying the operating knob 28.

In order that the operator may be apprised through sense of touch of the amount of angular turning movement imparted to the knob or handwheel 29, a detent arrangement is employed for releasably restraining this knob in successive angular positions. In the present instance a detent ball 40 (Fig. 5) is received in a bore 41 in the bracket 34 and is urged by a compression spring 42 against the face of a disk 43 rigid with the hub of the knob. A circularly arranged series of recesses 44 in the inner face of the disk are engaged by the ball one after another. Such recesses are spaced at equal angular distances about the rotational axis of the knob as, for example, twelve recesses each thirty degrees apart. Consequently the operator has the feeling of step-by-step indexing or notching of the operating knob when turning the same and can, through experience, calibrate his adjustments in terms of the number of "notches" that he turns the knob to attain a particular degree of color intensity.

Identical individually engageable couplings are provided between the drive shaft 35 and each of the series of adjusting screws 26 with which it is associated (see Figs. 8, 9, 10 and 11). Each of these couplings comprises a drive gear 45 and a companion driven gear 46 of the same number of teeth and pitch diameter disposed side-by-side on the drive shaft. Both the driving and driven gears are shown as spur gears. The drive gears 45 are in each instance fixed to the drive shaft, being integral with sleeves 47 pinned thereto, while the driven gears 46 are loose on the shaft, being integral with sleeves 48 freely journaled on the shaft. The sleeves 47, 48 telescoped on the drive shaft 35 alternate with each other in an end-to-end series restrained against axial movement as a whole with reference to the shaft. Freely revoluble spur type coupling pinions 49 are provided for coupling the drive gears to their companion driven gears to revolve in unison therewith. Each pinion is broad enough for simultaneous mesh with its associated pair of driving and driven gears and is bodily movable in a direction generally transaxial of the latter into and out of mesh with the same.

To swing the coupling pinions 49 into and out of mesh with their associated pairs of gears 45, 46, such pinions are journaled on pins 50 extending transversely across the bifurcated inner ends of levers 51 pivoted at 52 on brackets 53a (Figs. 9 and 10). The pinions are thus located beneath the associated pairs of gears to swing upward into mesh therewith or downward out of mesh. The opposite or outboard ends 51a of the levers 51 are elongated and serve as armatures coacting with associated operating electromagnets 53. Both the levers 51 and brackets 53a are made of steel or other ferrous metal for completion of the electromagnet flux path through them. Each electromagnet com-

prises an energizing winding 54 encircling an upright central core 54a which underlies the outboard end of the corresponding lever 51.

Torsion springs 55 may, if desired, be arranged to surround the mounting pins 52 for the levers 51 (Figs. 8 and 9) and yieldably urge the latter to tilt in a direction for disengagement of the coupling pinions 49 from their associated gears 45, 46 (counterclockwise as viewed in Fig. 9). To swing the levers in an opposite (in this case upward) direction for movement of their coupling pinions into gear-engaging position, it is necessary merely to energize the associated electromagnet 53, thereby rocking the levers 51 clockwise from the position indicated in Fig. 9.

To preclude the possibility of any such interference between the teeth of the pinions 49 and their associated gears 45, 46 as would preclude proper mesh on approach of the pinions to the gears, pointed teeth are preferably used. In addition, the addendum of one gear in each pair is desirably slightly less than that of the other although their pitch diameters are the same.

The energization of each electromagnet 53 is 25 under the control of a corresponding one of the selector switches 30 on the panel 31. Shifting of each selector switch 30 to its "on" position connects its associated electromagnet actuating winding 54 across a pair of suitable supply lines L1, L2 (Fig. 6), whereas restoration of each 30 switch to its "off" position open-circuits such winding. The extra contacts on the switches 30 are used to control a pilot lamp 56 for the bank of switches, such lamp being wired as shown so that whenever any one or more of an associated group of switches 30 is "on" the pilot lamp above the panel (Fig. 4) will be lighted.

The electromagnetically operated coupling arrangement described above is advantageous in a 40 number of respects. For one thing, it will be perceived that it obviates the use of axially shiftable clutch elements as, for example, on the drive shaft 35, both the driving and driven gears on the latter shaft being restrained against endwise movement at all times. The problem of backlash incident to wear of clutch teeth is eliminated since the coupling pinions 49 retain the teeth on the driving and driven gears 45, 46 in registry whenever meshed therewith, even though such 45 teeth may become worn in use. Moreover, the arrangement is such as to require so little power on the part of the electromagnets 53 in moving the coupling pinions 49 into mesh that simple, 50 low cost relay magnets such as those illustrated 55 may be employed instead of the more powerful solenoids commonly required for operating clutches. A winding drawing 35 milliamperes at 32 volts has been found adequate for present purposes. Two factors in the arrangement contribute to this low power requirement. First of all, 60 the lever arm about the pivot pin 52 of the outboard or armature portion of the lever 51 is substantially greater than that of the inboard portion carrying the pinion. Secondly, and of 65 even more importance, the component of the load force on the meshing pinion and gear teeth tending to separate the pinion from the gears is but a small fraction of the load. With conventional $14\frac{1}{2}^\circ$ teeth on the pinion 70 and gears such component is only approximately one-seventh of the tangentially applied load component. Consequently, only a comparatively light pull by the electromagnets 53 is required to retain the associated pinions in meshing position.

Drive connections from each of the driven gears 46 to their associated adjusting screws 26 are desirably established through worms and worm gears 57, 58 (Figs. 8, 9, 10 and 11). In the present instance the worms 57 are fashioned on the sleeves 48 of the driven gears 46, whereas the worm gears 58 are impositively coupled to the adjusting screws by friction or slip type connections. By utilizing self-locking or non-reversible worms and slip type connections as noted, it is possible to turn the screws 26 individually by hand without rotating the worms and worm gears associated therewith, and it is also possible to arrest positively the rotation of individual screws by limit stops hereinafter described without stopping rotation of the worms. In the instant embodiment the slip type connections include collars 59 pinned to the intermediate portions of respective screws, the worm gears being abutted against the upper faces of such collars with the worm gears freely revoluble on the screws. Springs 60 interposed between the upper face of each worm gear and a pair of adjusting nuts 61 threaded on the associated screws press the worm gears into frictional contact with the collars to turn therewith except when a worm gear is positively held against rotation by its associated worm, or a screw held against further turning by one of its stops hereinafter described. Such springs 60 are made of resilient sheet metal, being centrally apertured for passage of the screw therethrough, and are of cruciform shape with their laterally projecting arms curled downward and inward to bear against the upper faces of the washers 60a resting on the worm gears. This general type of compression spring is particularly advantageous, as compared to a coil spring, in that it has no tendency to wind up during rotational adjustment of the screw as would a coil spring.

A second leaf type spring 62 (Fig. 8) is located on the opposite or lower side of each of the collars 59 and serves to urge the adjusting screws 26 yieldably upward to prevent play of the screws in the tapped holes 27. These springs 62 each comprise a retangular strip of metal centrally apertured to receive the screw and having downwardly bent ends resting on the face of a pad 63 provided in the housing 23.

Laterally projecting finger grips 64 pinned to the upper ends of the adjusting screws 26 perform three different functions. First, they serve as a convenient grip for turning the screws by hand, such manual adjustment being optionally available in lieu of operation from the control stations 28, second, they serve as position signals for the adjusting screws, and, third, they coact with pairs of stop pins 65, 66 to limit positively the range of adjustment for the screws. In the present instance such stop pins 65, 66 are shown (Figs. 7, 8 and 9) as fixed to a cover plate 67 closing the top of the housing 23 and are spaced to limit the rotation of each adjusting screw to less than one full revolution, the permitted range of movement being approximately ninety degrees for each screw in the illustrated arrangement.

The range of rotational adjustment for the screws 26 permitted by the stops 65, 66 is carefully correlated with the permissible range of movement for the film regulating blades 20. In actual practice the spacing *c* between the fountain and pick-up rollers 17, 19 (Fig. 3) is of the order of .006 or .007 inch and the stops 65 which determine the nearest approach of the blades to the fountain rollers are set for a spacing of about .001 or .002 inch between blade and roller. The

spacing at the other or opposite limit position of the blades determined by the pins 66 is of the order of .015 to .020 inch. With a portion of one of the blades 20 in its limit position for minimum clearance from the fountain roller, such portion is spaced a lesser distance than the clearance between the fountain and pick-up rollers. Consequently, the ink film on the fountain roller is so thinned by that portion of the blade that there is no transfer to the pick-up roller in that zone, the feed of ink being thereby cut off for a width on the press equal to the length of the portion of the blade so spaced. The blade is, however, even in such zero ink delivery limit position, still spaced from the fountain roller so that there is no actual contact between the two, the wear and abrasion which would be incident to contact being therefore avoided. The maximum spacing position of the blade from the fountain roller corresponds substantially to a flooding condition for the fountain roller. The screw travel is, however, so selected with reference to the blade travel that the screw will not leave contact with the blade before coming in contact with its corresponding upper limit stop 66. In other words, the screw comes up against the stop 66 before the blade quite reaches its straight or completely unflexed position. In that manner play or idle screw movement which would be necessarily attendant upon the screw leaving contact with the blade is precluded.

It will be perceived that the dimensional requirements for the adjustable spacing of the blades 20 with reference to the fountain rollers 17 are such that great nicety and precision of adjustment are requisite. It is for that reason that the heretofore described arrangements for minimizing backlash or play between the parts of the adjusting mechanism are of particular importance. Moreover, the described arrangement is such that a turning movement of large magnitude for the operating knob 29 is used in moving the blades through their range of but a few thousandths of an inch, the turning movements of the screws 26 being, in other words, fractionally proportionate to turning of the knob 29. As to that, it will be noted that the ratio of connections shown from the operating knob 29 to the drive shaft 35 and thence to the worms 57 is 1 to 1. The worms and worm gears 57, 58 are ratioed, however, to give a substantial reduction as, for example, 20 to 1. If then the adjusting screws have, for example, a 24 pitch thread, each full revolution of the operating knob 29 results in a blade movement of only approximately .002 inch.

The drive mechanism shown herein as applied to the adjusting screws 26 constitutes, per se, the subject matter of my copending application, Serial No. 595,279, filed May 23, 1945, and which is a division of the present application.

Operation

The operation of the illustrated apparatus will, in general, be clear from the foregoing. By way of brief recapitulation, it may be assumed that the press unit 10 is running. The operator observes the printed matter delivered by the press from time to time. Whenever he finds that some particular column or columns need to be increased in color intensity, he has only to go to the appropriate control station, flip the selector switches 30 to their "on" positions for the columns in question and turn the operating knob 29 in the direction marked "Increase." As he

turns the operating knob he feels its step-by-step or notching action and on the basis of experience gives the selected column or columns as many "notches of color" as he thinks are required. Should the adjustment prove to be too great or too little he has only to turn the operating knob 29 in the appropriate direction another notch or more, or even a fraction thereof since the knob will remain stably in position with the detent 48 out of one of the recesses 44. The same procedure is of course followed to decrease the color intensity of a particular column or columns except that the operating knob 29 is turned in the "Decrease" direction. In either event, the throwing of the selected switches 38 to their "on" positions energizes the corresponding electromagnet actuating windings 54, thereby causing the electromagnets 53 to swing their associated coupling pinions 49 up into meshing position to couple their companion adjusting screws 26 to the drive shaft 35 for turning of the screws, when the operator turns the latter shaft, by the operating knob.

Whenever one of the bank of selector switches 38 is in its "on" position (exemplified by the lefthand switch in the top row of the panel shown in Fig. 4) the associated signal lamp 56 is lighted, thereby warning the operator that one of the windings 54 is still on so that he will not go away and leave it, or, more important, start to make an adjustment when some previously actuated selector switch is "on" and that he might not otherwise have noticed. The positions of the handles 38a of the several selector switches 38 indicate visually at all times the particular adjusting screws which are conditioned for actuation from the control station and those which are disabled against such actuation. While making the adjustments described, the operator can conveniently watch the finger pieces 64 on the upper ends of the series of adjusting screws and which act as signal flags to show continuously the positions of angular adjustment of the various screws.

In some instances the operator may desire to cut out of service an entire page width of the press unit. For that purpose the operator has only to throw the appropriate selector switches 38 for that page to their "on" positions and then turn the operating knob 29 in the "Decrease" direction until the finger pieces 64 of the selected series of screws all come up against their lower limit stops 65. Even if some of the adjusting screws in the selected group reach their stop position before the others being turned, the operator can go right on turning the operating knob 29 without interruption since the frictional or slip type connections between worm gears 58 and the screw-carried collars 59 will thereafter permit the worm gears of the stopped screws to continue rotation without imparting further motion to the screw or screws which have abutted against their stops.

In a similar manner, if it is desired to restore all of the adjusting screws 26 to like angular positions for some reason, that can be accomplished by turning on all of the selector switches and then rotating the operating knob 29 until the finger pieces 64 of the whole series of screws have come up against a like one of their available pair of limit stops 65, 66. Normally the screws would be turned to their zero delivery limit position for such purpose rather than to the other or flooding limit position. Simultaneous increase or decrease in the inking for a full page width often

contributes to ease of operation. For example, if the plates are changed on the press to print a picture page in lieu of a want-ad page of a previous edition, it is necessary to increase the inking for the full page. That can conveniently be done herein simply by shifting to "on" the selector switches 38 for the entire page in question and turning the knob 29 the required amount.

Prevention of so-called "blade buckling" is 10 facilitated by the disclosed arrangement. In the absence of some indicator, such as the finger piece 64, to show individual screw positions, it is often difficult to detect extreme flexure of some portion of the blade, especially because of 15 the effect of the inking mechanism rollers 14 in spreading the ink, it being necessary to check the blade with a gauge to make certain of blade position if no indicator is provided. Extreme flexure of a portion of the blade through over- 20 adjustment of one of the screws is likely to cause it to abrade the fountain roller and, in addition, such excessive distortion of one portion of the blade may interfere with proper flexing adjustment of an adjacent or even fairly remote portion. The positive stop arrangement herein disclosed limits the blade flexure safely to prevent contact with the fountain roller and the finger pieces 65 make it a simple matter to check at any time the degree of flexure of various portions 25 of the blade.

Should the selective adjustment arrangement 30 become disabled for any reason as, for example, by power failure, the operator still has full control of the inking through manual adjustment 35 of the individual screws 26. Each screw can be turned by grasping its finger piece 64 and turning the same. Even though the worm 57 associated 40 with a screw so turned should at the moment be coupled to the drive shaft 35, still no turning movement would be imparted to any other screw likewise coupled to the drive shaft because of the self-locking character of the worm and worm wheel combinations 57, 58. Being self-locking or 45 non-reversible, the worm wheels remain stationary during the rotation of the screws relative to them permitted by the slip connections at 58, 59.

I claim as my invention:

1. In an adjusting mechanism for a printing press ink fountain having a revoluble fountain roller and a laterally flexible blade extending along the same for regulation of the ink film thickness on said roller in accordance with lateral flexure of the blade toward and from the latter, the combination of a support extending longitudinally of the blade and having a series of adjusting screws threaded therein to bear against a side face of the blade generally normally thereto for lateral flexure of said blade in accordance with the endwise displacement of said screws incident to rotation thereof, positive stop means coacting with each of said screws for limiting the rotation thereof to a fixed angular distance correlated with the permissible range of flexure of said blade with reference to said roller, a drive shaft, and means including individual slip type drive connections for connecting each of said screws in driven relation with said shaft.
2. In an adjusting mechanism for a printing press ink fountain having a revoluble fountain roller and a laterally flexible blade extending along the same for regulation of the ink film thickness on said roller in accordance with lateral flexure of the blade toward and from the latter,

the combination of a support extending longitudinally of the blade and having a series of adjusting screws threaded therein to bear against a side face of the blade generally normally thereto for lateral flexure of said blade in accordance with the endwise displacement of said screws incident to rotation thereof, a radial projection on each of said screws and rotatable therewith, and positive stop means coacting with each of said projections for positively limiting the rotation of the screws in the turning of the latter in a direction therefor which results in flexure of the blade toward the fountain roller.

3. In an adjusting mechanism for a printing press ink fountain having a revoluble fountain roller and a laterally flexible blade extending along the same for regulation of the ink film thickness on said roller in accordance with lateral flexure of the blade toward and from the latter, the combination of a support extending longitudinally of the blade and having a series of adjusting screws threaded therein to bear against a side face of the blade generally normal thereto for lateral flexure of said blade in accordance with the endwise displacement of said screws incident to rotation thereof, positive stop means coacting with each of said screws for limiting the rotation thereof to a fixed angular distance correlated with the permissible range of flexure of said blade with reference to said roller, a drive shaft, selectively operable means for coupling selected screws in driven relation with said shaft, and slip type connections interposed in said coupling means between each of said screws and said shaft to permit turning of the latter after motion of any screw or screws coupled to said shaft has been arrested by their stop means.

4. In an adjusting apparatus for the ink delivery mechanism of a printing press unit, the combination of a press-wide series of rotatably adjustable devices arranged at intervals across the press for severally regulating the ink supply to corresponding columnar portions of the press unit, a control panel including means for mounting the same on one side of the press unit and having thereon a plurality of selector switches corresponding to respective ones of said devices, a single drive shaft extending along said series of devices in adjacency thereto and transversely of the press unit, means operable in accordance with the manipulation of said selector switches for coupling and uncoupling respective ones of said devices to said drive shaft, mechanical stop means associated with each of said devices for positively limiting the range of angular adjustment therefor, slip type connections interposed between each of said devices and said drive shaft to permit continued rotation of the latter after a stoppage of one or more of said devices by their associated stop means, and means operable from a point adjacent said panel for effecting rotation of said shaft.

5. In an adjusting apparatus for the ink delivery mechanism of a printing press, the combination of a series of movably adjustable devices arranged at intervals across the press for severally regulating the ink supply to corresponding columnar portions of the press over a multi-page width of the latter, each of said devices being adjustable between a zero ink delivery position therefor and an opposite or maximum delivery position, means for effecting individual adjusting movement of said devices, and means including slip type drive connections for shifting any selected page-wide group of said devices simul-

taneously toward their zero delivery position and stop means for automatically arresting individual ones of the group upon their arrival at such zero delivery position to cut out of operation a page-wide section of the press.

6. In an adjusting apparatus for the ink supply mechanism of a printing press, the combination of a series of manually adjustable devices arranged at intervals across the press for severally regulating the ink supply to corresponding columnar portions of the press, each of said devices being adjustable between a zero ink delivery limit position therefor and an opposite or maximum ink delivery limit position, means for effecting individual adjusting movement of said devices, and means including slip type drive connections for shifting any selected group of said devices simultaneously toward either of their alternatively available respective limit positions and stop means for automatically arresting the movement of individual ones of the group upon their arrival at such limit position.

7. In an adjusting mechanism for a printing press ink fountain having a revoluble fountain roller and a coacting blade extending along the same and which is laterally flexible with reference to the roller for regulating the thickness of ink film on the latter, the combination of an adjusting screw, means threadably supporting said screw in a position generally normal to a side face of the blade for lateral flexure of the blade by the endwise movement of said screw incident to rotation of the same, a drive gear freely journaled on said screw, means frictionally engaging said gear and screw to connect the same impositively for rotation in unison so long as both are free to turn and permitting slippage therebetween when either is held against rotation, and positive stop means coacting with said screw for fixedly limiting the rotation thereof to an angular distance correlated with the permissible range of flexure of the blade with reference to the roller.

8. In an adjusting mechanism for a printing press ink fountain having a rotatable fountain and pick-up rollers disposed in parallel relation with their peripheries spaced apart a distance of the order of a few thousandths of an inch and a laterally flexible blade projecting toward said fountain roller for regulating the thickness of the ink film on the latter, the combination of means including an adjusting screw threaded in a fixed support adjacent said blade and bearing against a side face of the latter for flexing said blade laterally to adjust the thickness of said ink film, positive stop means coacting with said screw to define alternate limit positions therefor in one of which the blade is flexed so far toward said fountain roller as to diminish the ink film on the latter to less than the spacing between the pick-up and fountain rollers while still retaining the blade out of contact with the latter and in the other of which limit positions the blade is sprung far enough away from the fountain roller for substantial flooding of the latter but with said screw still in contact with the blade, a drive shaft, and a slip type drive connection associated with said drive shaft for revolving said adjusting screw whereby continued operation of the drive shaft without further rotation of the screw is permitted after engagement of the latter with said stop means.

9. In an adjusting mechanism for a press ink fountain having a revoluble fountain roller and a coacting blade extending along the same and which is laterally flexible with reference to the

roller for regulating the thickness of ink film on the latter, the combination of an adjusting screw having an operating handle adapting the same for manual rotation, means threadably supporting said screw generally normal to a side face of the blade for lateral flexure of the blade by the endwise movement of said screw incident to rotation of the same, a worm gear journaled on said screw coaxially therewith, a self-locking worm meshed with said worm gear for revolving the latter, positive stop means coacting with said screw for fixedly limiting the rotation thereof and to an arc correlated with the permissible range of flexure of the blade with reference to the roller, and means frictionally connecting said gear and screw for rotation in unison while both are free to turn and permitting either to turn relative to the other when such other is positively held against rotation, whereby said screw may be turned manually while said gear remains stationary due to the self-locking action of said worm thereon or said gear turned by said worm while said screw is held stationary by said stop means.

10. In an adjusting mechanism for a press ink fountain having a revoluble fountain roller and a coacting blade extending along the same and which is laterally flexible with reference to the roller for regulating the thickness of ink film on the latter, the combination of an adjusting screw, means threadably supporting said screw generally normal to a side face of the blade for lateral flexure of the blade by the endwise movement of said screw incident to rotation of the same, a drive gear freely journaled on said screw, said screw having a collar rigid therewith presenting a face opposed to an end face of said gear, a sheet metal spring interposed between said collar and the opposed end face of said gear, said spring being positioned to thrust against said gear and force said opposed faces of said collar and gear into frictional contact with each other to establish an impositive connection between the collar and gear, and positive stop means coacting with said screw for fixedly limiting the rotation thereof to an arc correlated with the permissible range of flexure of the blade with reference to the roller.

11. In an adjusting mechanism for a press ink fountain having a revoluble fountain roller and a coacting blade extending along the same and which is laterally flexible with reference to the roller for regulating the thickness of ink film on the latter, the combination of an adjusting screw, means threadably supporting said screw generally normal to a side face of the blade for lateral flexure of the blade by the endwise movement of said screw incident to rotation of the same, said screw having a collar rigid therewith intermediate its ends, a spring interposed between said collar and said support yieldably urging said screw endwise in one direction irrespec-

tive of its rotation to prevent end play of said screw in said support, a drive gear freely journaled on said screw on the opposite side of said collar, means including a second spring positioned to bear against said gear and force the latter into frictional contact with said collar for connecting the same impositively for rotation of the screw in unison with the gear so long as the screw remains free to turn and permitting slippage of the gear with reference thereto when the screw is held against rotation, and positive stop means coacting with said screw for fixedly limiting the rotation thereof to an angular distance correlated with the permissible range of flexure of the blade with reference to the roller.

12. In an adjusting mechanism for a printing press ink fountain having regulable means for delivering ink, the combination of means including a rotatable member for adjusting the rate of delivery of said regulable means in accordance with the angular displacement of said member, stop means coacting with said member to limit positively its adjustment in at least one direction, together with a slip type drive connection to said member for turning the same.

13. In an adjusting mechanism for a printing press ink fountain having regulable means for delivering ink, the combination of means including a threadably mounted member for adjusting the delivery rate of said regulable means in accordance with the axial displacement of said member incident to rotation thereof, mechanical stop means coacting with said member for positively limiting the rotational adjustment thereof in at least one direction, and a slip type drive connection to said member for turning the same.

EMORY W. WORTHINGTON.
